W. C. ROE

PROTECTIVE COVERING

Filed Aug. 30, 1921

Inventor:

William C. Roe
by Hubert A. Patterson Atty.

UNITED STATES PATENT OFFICE.

WILLIAM C. ROE, OF NEW YORK, N. Y., ASSIGNOR TO HOLMES ELECTRIC PROTECTIVE COMPANY, OF NEW YORK, N. Y., A CORPORATION OF NEW YORK.

PROTECTIVE COVERING.

Application filed August 30, 1921. Serial No. 497,001.

To all whom it may concern:

Be it known that I, WILLIAM C. ROE, a citizen of the United States, residing at New York, in the county of New York, State of New York, have invented certain new and useful Improvements in Protective Coverings, of which the following is a full, clear, concise, and exact description.

This invention relates to improvements in electrical alarm systems and particularly to protective devices used in connection therewith which devices serve as detectors causing an operation of the alarm system when the devices are destroyed by fire, water, burglars or any other cause.

More specifically, the protective device comprises a protective covering formed of fragile material and provided with electrical conductors of such a type and so secured thereto that a destruction of the covering results in either a destruction of the conductors or the creation of a short circuit between them. The protective covering is so constructed that it is particularly adapted for application to the walls of a room or other enclosure in much the same manner as ordinary wall paper, and is so designed that when applied, the electrical conductors are invisible and the covering presents a neat and pleasing appearance.

Other objects and advantages of the present improvement will be set forth in detail in the following specification and particularly pointed out in the appended claim.

In the accompanying drawings which illustrate one embodiment of the invention,

Fig. 1 is a fragmentary front elevation of the protective covering, a part thereof being bent back to show the electrical conductors.

Fig. 2 is an enlarged sectional view of the protective covering shown in Fig. 1.

Fig. 3 is a fragmentary perspective view of a portion of a room and showing protective covering made in accordance with the invention applied to the walls and ceiling thereof.

Fig. 4 is a fragmentary detail illustrating one manner of applying the covering.

Referring now to the drawings in which like reference numerals designate similar parts throughout the several views, the protective covering comprises strips of paper 5 and 6 which, for convenience in handling, have a width of approximately 36 inches and a length of 100 feet or more. The strips

of paper are secured together by means of asphaltum 7 or other suitable material which also serves to secure between them electrical conductors 8 which are formed of metal foil. The conductors 8 are first dipped in asphaltum and then arranged between the strips of paper 5 and 6 in spaced relation to each other extending lengthwise of the paper strips. The conductors 8 are spaced 3 inches apart, each outside conductor being spaced one and one-half inches from each edge of the strip to form a portion 9, the purpose of which will be herein-after described.

In order that the covering may be fragile, for reasons hereinafter explained, and also readily applied to the walls and ceiling of a room or other enclosure with paste in much the same manner as wall paper is applied, or by any other suitable means, the completed covering is made as thin as possible. The paper strips have a thickness of approximately six thousandths of an inch (.006"), the foil one thousandth of an inch (.001"), and the asphaltum about eight thousandths of an inch (.008") making the entire thickness of the covering in the vicinity of two hundredths of an inch (.02").

By making the covering of small thickness, it is rendered fragile to a considerable degree so that it is readily destroyed by fire, the presence of water in any considerable quantity, or may be easily torn by burglars or other unauthorized persons in an attempt to cut through the surface to which the paper is applied or in an attempt to remove the paper from the said surface. Furthermore, since the foil has a thickness even less than the thickness of the paper, in tearing or cutting the paper the continuity of the foil will also be readily broken, giving no indication of the presence of the foil until it has been broken in cutting or otherwise destroying the paper.

It is preferable that the asphaltum 7 be applied to the layers of paper and strips of foil in such a manner that the outer surfaces of the layers of the paper are smooth and give no indication of the presence of the foil therebetween, as is clearly shown in Fig. 2.

Asphaltum is preferably selected as the substance for securing the strips of paper and the foil together both for its adhesive qualities and because it is impervious to

moisture, which is of advantage when the paper is applied to walls or other surfaces which may be damp. Although the asphaltum is sufficient to resist dampness and prevent it from affecting the electrical conductors 8, the protective material as a whole is not sufficiently strong to resist considerable water so that in case the surface to which the covering is applied should become flooded, the water would eventually reach the conductors 8, causing a short circuit between them. Also due to the fragile construction of the covering, it is easily destroyed by fire, causing the conductors 8 either to be destroyed or come in contact with each other causing a short circuit.

The protective covering herein disclosed is especially adapted for use in alarm systems of well-known type which have been used for a number of years, in which the alarm devices of the system are actuated through a change in the resistance of the wiring of the system of which the foil conductors 8 constitute a part. In case the conductors 8 are destroyed by fire, water, burglars or other cause, infinite resistance is introduced within the circuit, causing an operation of the signaling devices therein, or in case the foil conductors 8 are short circuited due to any cause, the resistance in the circuit is changed, also causing an actuation of the signaling devices.

The protective covering is made up in rolls which may be applied to the walls and ceiling of a room or other enclosure in much the same manner as wall paper is applied, or may be applied in the manner illustrated in Fig. 3 in which the protective covering is shown applied to the walls and ceiling of a room, the strips being applied lengthwise so that the foil conductors 8 run up and down the wall and across the ceiling. The strips of covering are secured to the walls and ceiling by retaining strips 10, constructed of wood, nails or screws passing through the retaining strip and portions 9 of the covering which are overlapped as is shown in Fig. 4. Cross stripping 11 is secured between the stripping 10. The foil conductors 8 are con-

nected in any suitable manner to conductors 12 housed within the floor board 13 and molding 14, the conductors 12 constituting part of the alarm circuit. The means for connecting the foil conductors 8 to the conductors 12 may be of any suitable type and have not been shown for the reason that the manner of connecting the foil conductors to the other parts of the alarm system constitutes no part of the present invention. Although the means just described for securing the covering is preferred, it is to be understood that the covering may be applied in a variety of different ways without departing from the spirit and scope of the invention. For instance, in some cases it may be found desirable to apply the covering to the floor as well as to the walls and ceiling as previously described.

Although the materials specified herein for the production of a protective paper are thought preferable, it is to be understood that the invention is not limited to a protective covering having the specific construction disclosed herein, the invention being present in any protective covering comprising two layers of material with electrical conductors between them, the layers of material and foil held together in any suitable manner to form a unitary structure, one layer of the material lying adjacent the surface to which the covering is secured and the other layer serving to cover the conductors and render them invisible.

What is claimed is:

A multi-ply waterproof fabric comprising superposed plies, a layer of asphalt securing said plies together, and thin, flat, asphalt coated, metallic ribbons embedded in the asphalt layer, the asphalt layer having a thickness not less than the thickness of the ribbons, whereby the outer surfaces of the plies are disposed entirely in one plane and the presence of the ribbons concealed.

In witness whereof, I hereunto subscribe my name this 25th day of August A. D., 1921.

WILLIAM C. ROE.
